UNITED STATES PATENT OFFICE.

EDWIN E. WAITE, OF FRAMINGHAM, MASSACHUSETTS, ASSIGNOR OF ONE-HALF TO
STANDARD WOVEN FABRIC COMPANY, OF FRAMINGHAM, MASSACHUSETTS, A COR-
PORATION OF MASSACHUSETTS.

FABRIC AND METHOD OF MAKING THE SAME.

1,281,723.

Specification of Letters Patent. Patented Oct. 15, 1918.

Application filed November 17, 1914. Serial No. 872,644.

To all whom it may concern:

Be it known that I, EDWIN E. WAITE, a citizen of the United States, residing at Framingham, in the county of Middlesex 5 and State of Massachusetts, have invented certain new and useful Improvements in Fabrics and Methods of Making the Same, of which the following description, in connection with the accompanying drawings, is 10 a specification, like reference characters on the drawings indicating like parts in the several figures.

This invention relates to belts of the type used for mechanical purposes, and to methods of manufacturing such belts.

Many attempts have been made to produce an endless belt of textile fabric that would make a satisfactory substitute for the leather belts now in general use for mechanical purposes, but great difficulty has been experienced in making such a belt on a commercial basis which would have the required degree of flexibility and would avoid the presence of a lap or splice. The present invention 25 provides a belt which is not open to either of these objections and also provides a novel method of making the same.

The invention will be readily understood from the following description, reference 30 being made to the accompanying drawings, in which—

Figure 1 is a view in side elevation showing one step in the process of manufacture of the fabric, and also showing diagrammatically the more essential elements of an apparatus, with the aid of which the practice of this method may be facilitated;

Fig. 2 is an angular view showing a part of the apparatus shown in Fig. 1, and illustrating a later step in the process of manufacture of the fabric;

Fig. 3 is an angular view of a small portion of a fabric made in accordance with this invention, the threads or yarn composing the fabric being shown widely separated or spread apart for the purpose of more clearly illustrating the structure of the fabric; and

Fig. 4 is a view similar to Fig. 3 showing a modified form of fabric.

50 Briefly stated, the fabric consists of a warp and a weft, one of these parts being arranged to form stitches by which it is united to the other part. According to the

preferred practice, the weft is laid first and the warp is then stitched into it.

The method may be conveniently practised by supporting the weft on a pair of flexible bands or chains 1 having circumferential dimensions substantially equivalent to that of the belt to be manufactured. 60 These bands are shown in Fig. 1 as supported on three pairs of pulleys or wheels indicated, respectively, by the numerals 2, 3 and 4. The wheels may each have a series of pins projecting from its periphery, these 65 pins being arranged to enter holes in the bands 1 so that, by driving one pair of wheels, both bands will be driven at the same speed. Preferably the bands are made

of metal and along the inner edge of each 70 band a series of spurs 5 is formed. The spurs of the two series are staggered with relation to each other; that is, the spurs of one series lie opposite the space between the adjacent spurs of the other series. The weft *a* is laid 75 or stretched on these bands 1, the end of the weft at the start being caught under a spur 6 in one of the bands, or secured in any other convenient manner; and the weft is then strung back and forth, as shown in Fig. 80 2, to form a series of parallel strands lying transversely across the space between the bands, the turns at the ends of the strands being supported by the opposite series of spurs 5. The weft may be laid by hand or

85 a yarn guide 7 may be employed, this guide being mounted to reciprocate back and forth from one series of spurs 5 to the other, while the bands 1 are fed forward step by step as the guide arrives at the opposite limits of its 90 stroke. When the laying of the weft has been completed, the end of the weft is secured under a spur 8 like the spur 6 but on the other band and substantially opposite the spur 6, as shown in Fig. 2. It will be 95 observed that, by this arrangement, the weft is laid in the form of an endless belt, the threads or strands being spaced substantially equi-distant around the circumference 100 of the belt.

As above stated, the warp is stitched into the weft. The stitching may be done by hand or by the aid of any suitable type of stitch forming mechanism. Inasmuch as some form of automatic stitch forming 105 mechanism or sewing machine is always used

in practice, such a mechanism is shown in the drawings, being indicated diagrammatically, by the needle 9 and the shuttle 10. The warp is supplied in the form of a 5 pair of threads, one thread *b* being inserted by the needle 9 and the other thread *c* by the shuttle 10. The stitch forming mechanism shown is of the lock type and as this mechanism operates to form the series of stitches, 10 the bands 1 are fed forward step by step at such a rate that, in the arrangement shown, each stitch jumps two weft threads or strands *a* of the weft; that is, two strands of the weft extend through the loop of each 15 stitch of the warp. This structure is clearly shown in Fig. 3. While the bands are being fed forward and the stitch forming mechanism is making a series of stitches along one edge of the belt, the bands 1 and the 20 stitch forming mechanism are given a relative lateral movement of sufficient extent to cause the second series of stitches to lie beside and close to the first series, that is, this lateral movement causes the warp to be 25 stitched into the belt in a series of turns forming a spiral of very slow pitch. An odd number of threads or strands *a* of the weft are carried by the bands 1 so that, as the stitch forming mechanism starts to 30 stitch in the second turn of the warp, the stitches will come between the strands that previously were jumped and each pair of strands now jumped will be those lying on the opposite sides of each interlocked portion 35 of the stitches of the first series, as shown in Fig. 3.

The stitching and feeding operations are continued until the entire surface of the weft between the bands 1 has been filled in 40 by the turns or convolutions of the warp. The ends of the warp threads *b* and *c*, both where the stitching started and where it was stopped, are tied or fastened to the belt in any convenient manner to prevent raveling. 45 The belt is then completed. A portion of the belt appears substantially as indicated in Fig. 3. Obviously the length of the stitch and the number of threads of the weft jumped by each stitch may be varied as circumstances require. The operation of filling 50 the warp into the weft may be commenced while the weft is being laid.

By moving one of the pair of wheels 2, 3 or 4 toward the other two pairs, the bands 55 1 may be slackened sufficiently to permit the removal of the belt in its completed condition.

In Fig. 4 is shown a portion of a belt made by the method above described, but in this 60 case the warp has been manipulated to form stitches of the chain type instead of the lock type, as in the fabric shown in Fig. 3. Accordingly in this modified form only one warp thread is required.

65 By making a proper selection of thread or

yarn from which to manufacture the belt its degree of flexibility may be varied and it may be made heavy or light as desired, within reasonable limits. It is obvious that the belt is uniform in structure and is literally 70 endless, having no lap or splice. Furthermore a belt of this character can be manufactured very economically.

While certain elements of an apparatus have been shown in the drawings and have 75 been referred to above for the purpose of explaining more clearly this method and a convenient way of practising it, it will be understood that this method is not limited to use with any specific form of apparatus 80 but that it may be practised by hand or with the aid of many different mechanisms and apparatus.

Having thus described my invention, what I claim as new and desire to secure by Letters Patent of the United States is:

1. An endless fabric belt devoid of a lap or splice and comprising independent sets of warp and weft threads interwoven with each other, one of said sets of threads being 90 arranged to form stitches through the loops of which stitches the other set of threads extends, whereby said stitches lock the warp and weft together.

2. An endless fabric belt comprising a 95 warp extending circumferentially a plurality of times around the belt in the form of a series of stitches and a weft extending through said stitches and binding the convolutions of the warp together.

3. An endless fabric belt of substantially uniform structure throughout its entire length having weft threads lying transversely of the belt and warp threads extending circumferentially of the belt and stitched 105 into the weft.

4. An endless fabric belt comprising a pair of warp threads extending circumferentially around the belt to form a plurality of turns lying side by side and a weft lying 110 transversely of the warp, said warp threads being stitched to the weft at their points of intersection with the weft.

5. An endless fabric belt devoid of a lap or splice and comprising a warp extending 115 circumferentially around the belt and a weft lying transversely of the belt, one of said parts being arranged to form stitches which unite it to the other part.

6. An endless fabric belt comprising a 120 warp arranged to form a series of stitches extending circumferentially around the belt in a plurality of turns lying side by side, and a weft binding said turns of the warp together.

7. An endless fabric belt comprising a 125 weft, a pair of warp threads lying on opposite sides of the weft and extending circumferentially around the belt to form a plurality of turns lying side by side, said 130

warp threads being interlocked with each other to form stitches which unite them to the weft.

8. That improvement in the art of making 5 endless fabric belts which consists in laying the weft in the form of an endless belt and stitching the warp into the weft in a plurality of circumferential turns.

9. That improvement in the art of making 10 endless fabric belts from warp and weft

threads, which consists in laying one set of threads in the form of an endless belt and stitching the other set of threads into the set so laid.

In testimony whereof I have affixed my 15 signature, in presence of two witnesses.

EDWIN E. WAITE.
